UNITED STATES PATENT OFFICE.

JOHN P. DORAU, OF NORTH FOND DU LAC, WISCONSIN.

DRIVING MECHANISM FOR WASHING-MACHINES.

1,273,337.

Specification of Letters Patent. Patented July 23, 1918.

Application filed August 18, 1917. Serial No. 186,864.

To all whom it may concern:

Be it known that I, JOHN P. DORAU, a citizen of the United States, and resident of North Fond du Lac, in the county of Fond du Lac and State of Wisconsin, have invented new and useful Improvements in Driving Mechanism for Washing-Machines, of which the following is a description, reference being had to the accompanying drawings, which are a part of this specification.

The invention relates to driving mechanism, and more particularly to a driving mechanism for a washing machine.

It is one of the objects of this invention to provide a driving mechanism for operating the shaft carrying the clothes pounder so as to produce several agitations and vertical reciprocations of the pounder in one direction and then by reversing the direction of turning of the drive shaft produce several agitations and vertical reciprocations of the pounder in the opposite direction with the result that the pounder, during the washing operation, will strike the clothes in different places and thus efficiently wash them.

A further object of the invention is to provide a bearing for the pounder shaft which will enable said shaft to be vertically reciprocated without interference with the so called apron usually disposed above the pounder shaft.

The invention further consists in the several features hereinafter set forth.

In the drawings:

Fig. 1 is a view of the device embodying the invention, parts being broken away and parts being shown in section;

Fig. 2 is a section taken on the line 2—2 of Fig. 1;

Fig. 3 is a modified form of driving connection between the pounder shaft and drive shaft;

Fig. 4 is a section taken on the line 4—4 of Fig. 3;

Fig. 5 is another modified form of driving connection between the pounder shaft and drive shaft.

The washing machine to which the driving mechanism is applied consists of a tub 5 and hinged cover 6, each of usual con-

struction, said cover carrying a bracket 7 in which the pounder shaft 8 is vertically slidably and pivotally mounted, said shaft carrying a pounder 9 of any suitable construction. A horizontal shaft 10 is secured 55 to the tub and has a fly wheel 11 mounted thereon provided with a groove 12 in which a round rubber band 13 is inserted and which band is adapted to be frictionally engaged by the wheel of a motor (not shown). 60 The construction above described serves to continuously rotate the wheel 11 however any other suitable means may be used to impart movement to the wheel 11.

Each form of the invention includes a 65 horizontally disposed drive shaft 14 journaled in the bracket 7, a driving connection between the shafts 8 and 14, and a driving connection between the shaft 14 and wheel 11 provides means for reversibly driving 70 said shaft 14 on the continuous rotation of the wheel 10.

In Figs. 1 and 2 the driving connection between the shafts 8 and 14 consists of an arm or crank 15 secured to the shaft 8 and 75 having a spherical knob 16 slidably and pivotally mounted in the bore 17 of a crank 18 connected to the shaft 14 to provide an offset joint connection with said shaft. This offset joint connection produces a back and 80 forth or agitating movement of the pounder shaft together with an up and down movement thereof on the rotation of the shaft 14. In order to relieve the pounder of excessive load I have provided a yielding connection 85 between the driving connection and the shaft 14 which is formed by slidably mounting the crank 18 in a bore 19 in a member 20 mounted on the shaft 14 and interposing a spring 21 between said member and crank 90 to permit relative yielding movement, the crank being guided and retained in operative position by a guide rod 22 and a guide and spring retaining rod 23.

In Figs. 3 and 4 I have shown a driving 95 connection between the shafts 8 and 14 using the same kind of offset crank connection but instead of the crank 18 I mount a gear 24 on the shaft 8 and provide a segmental gear 25 pivotally mounted on arms 100

26 on the shaft 8 and connected with said gear 24, with a cylindrical arm 25' pivotally and slidably mounted in the bore 17 of the crank 18. This construction also produces an agitating movement and vertical reciprocatory movement of the pounder shaft on the rotation of the shaft 14.

10 In Fig. 5 I have shown a driving connection between the shafts 8 and 14 showing a different manner of yieldingly connecting the crank on shaft 8 to that on the shaft 14. In this instance the crank 18' is directly connected to the shaft 14 and provided with a bore 17' in which the rounded end 16' of a 15 two part crank 15', 15'', secured to the shaft 8 is slidably and pivotally mounted. This two part crank comprises the part 15' secured to the shaft 8 and the part 15'' pivotally secured to the part 15' and yieldingly 20 movable downwardly with respect thereto by means of a spring 21 secured at its ends to the parts 15' and 15'' respectively. Like the other constructions this permits relative yielding movement of the pounder shaft 8 and agitates the said shaft in the same way as the construction shown in Fig. 1.

25 In each instance the means for reversibly driving the shaft 14 consists of an automatically reversible gear drive connection between the shafts 14 and 10. This comprises a member 27 journaled on a stud shaft 28, a gearing connection between said member 27 and the shaft 14, and means for continuously driving said member.

30 The gearing connection between the member 27 and the shaft 14 consists of a segmental bevel gear 29 on the member 27 adapted to work with either of two oppositely disposed bevel gears 30 and 31 on the shaft 14.

35 The means for driving the member 27 consists of a bevel gear 32 formed in the member 27 working with a bevel gear 33 loosely mounted on the shaft 14 and carrying a spur gear 34 meshing with a spur gear 35 carried by the fly wheel 11. Of course it will be understood that any suitable means may be provided for driving the member 27 to impart continuous rotary movement 40 thereto.

45 With these constructions the rotation of the shaft 14 will produce several agitations of the pounder in one direction and then several agitations in the reverse direction 50 during the vertical reciprocations of the pounder shaft 8, the reversal of the drive of the shaft 8 being accomplished by the alternate engagement of the gear 29 with the gear 30 and 31, the gear 29 being continuously driven. Since the pounder is alternately agitated for about a half revolution on either side of its mid position it strikes the clothes in different places during

its movements and thereby efficiently cleans them.

65

It is common practice in washing machines to dispose the so called apron above the upper bearing for the pounder shaft and unless the apron is moved in the usual constructions of machines it will be in the 70 way of that portion of the pounder shaft which rises above the upper bearing. To obviate the necessity for the reversal of the apron and to permit free movement of the pounder shaft without interference with the 75 apron I have provided a hollow bearing shaft 36 secured to the bearing arm 37 of the bracket 7, which shaft telescopes within the hollow pounder shaft 8 so that said shaft will not project above the arm 37 at its extreme upper position. The shafts 36 and 8 are made hollow because of the usual valve, not shown, which is carried by the pounder.

80

I am aware that the details of construction herein shown and described are subject 85 to some modification and change and I desire it to be understood that such changes as come within the scope of the appended claims, I deem to be within the spirit of my invention.

90

What I claim as my invention is:

1. In a driving mechanism, the combination, with a vertical shaft, of a drive shaft disposed at an angle thereto, a driving connection between said shafts for imparting 95 several oscillations and vertical reciprocations to said vertical shaft, and means for turning said drive shaft several times in one direction and then in the opposite direction to reverse the oscillations of the vertical 100 shaft.

2. In a driving mechanism, the combination, with a vertical shaft, of a drive shaft disposed at an angle thereto, a driving connection between said shafts having an offset 105 joint connection with one of said shafts, and means for automatically reversing the direction of rotation of the drive shaft after several rotations thereof.

3. In a driving mechanism, the combination, with a vertical shaft, of a drive shaft disposed at an angle thereto, a driving connection between said shafts having an offset joint connection with said drive shaft, a member continuously driven in one direction, and a reversible gear drive connection between said member and the drive shaft.

4. In a driving mechanism, the combination, with a vertical shaft, of a drive shaft disposed at an angle thereto, a driving connection between said shafts for oscillating and vertically reciprocating said vertical shaft on the rotation of the drive shaft, a shaft continuously driven in one direction, a segmental gear mounted on last named said 125 shaft, a pair of gears on the drive shaft

110

125

adapted to alternately mesh with said segmental gear for alternately rotating said drive shaft in opposite directions.

5. In a driving mechanism, the combination of a bracket having an upwardly projecting bearing arm, a hollow pounder shaft vertically slidably and pivotally mounted in

said bracket, a bearing shaft depending from said arm and adapted to telescope within the hollow of said pounder shaft, and 10 means for agitating and vertically reciprocating said pounder shaft.

In testimony whereof, I affix my signature.
JOHN P. DORAU.
